UNITED STATES PATENT OFFICE.

WM. H. LINDSAY, OF NEW YORK, N. Y.

WATER-METER.

Specification of Letters Patent No. 9,647, dated April 5, 1853.

To all whom it may concern:

Be it known that I, WILLIAM HENRY LINDSAY, of the city, county, and State of New York, have invented certain Improvements in Fluid-Meters and Hydraulic Engines, &c.; and to enable others skilled in the art to make and use my invention I do hereby declare that the following is a full and exact description of the said invention.

10 The principle or character which distinguishes my invention from others, in a machine or apparatus acted upon by a fluid, consists in 1st, the peculiar combination of devices and the method of operation, by 15 which the secondary engine with its valves is actuated and governed, combined with the same of the main or working engine and its valves, whereby certainty of action, smoothness of working, durability, and accuracy 20 is more perfectly attained and combined, than in any other engine or apparatus operated by water or other non elastic fluid in an analogous manner with which I am acquainted. 2d, in the means whereby independent 25 of all external appliances, the secondary engine, as also the main engine valves, are protected against an undue amount of travel in either direction, being a safety, or additional means provided to insure 30 that result, when employed in connection with the valves otherwise governing their travel, or the entrance and exit of the acting medium to and from the secondary engine. And when not so employed in connection therewith, checking its travel, and thereby 35 that of the main engine valves, by its own independent action. 3d, in the peculiar construction of the sluice or gridiron valves in the manner set forth, thereby relieving 40 them of a portion of the pressure they would as ordinarily constructed be subject to, which decreases the power requisite to put them in motion, and their friction.

I will now describe the construction and 45 operation of the machine, and then show wherein my improvements consist, reference being made to the accompanying drawings.

Figure 1, an elevation, on the side through 50 which the fluid enters; Fig. 2, central sectional elevation; Fig. 3, central cross elevation; Fig. 4, central cross section; Fig. 5, end elevation; Figs. 6¹ and 6², sections of the balanced gridiron valves and their seats, on the entrance side; Fig. 7, plan of one of 55 the valves, with the recesses, on its under or face side.

The drawings represent the apparatus at that part of the plungers (C¹ C²) travel in

the direction of the arrows when the cross head (D) has just come in contact with the 60 stud or jam nut (g¹) on the auxiliary engine's valve motion rod (f) which is the first step toward producing shifting of the auxiliary and main engine's valves, causing the reciprocating action of the machine. 65

Supposing the stop-valve W, to be wholly or partially open, the fluid whereby the machine is operated passes through the central opening a¹, on the entrance side of the bed plate A, thence into the water way b¹, from 70 which it passes by the opening c¹ c², through the side pipes T¹ T², into the entrance valve chests O¹ O², but the ports in the valve seats 2¹, being covered by the position of valve P¹, the fluid can only pass into the chamber or 75 cylinder B², and act upon the plunger C², by being at liberty to pass through the ports in the valve seat 2², they being uncovered by the position of the valve P², while by the action of the entering fluid on the plunger C², 80 the fluid in the cylinder B¹, is displaced therefrom by the plunger C¹, being forced forward in that direction, the fluid so displaced passing through the openings 4¹, 3¹ and 17³, into the discharge valve chest O³, by 85 the open ports in the valve seat 2³, which are uncovered by the position of the discharge valve P⁴ thereon, (the discharge ports of the cylinder B² being covered during the time that those of cylinder B¹ are open) from 90 whence it passes by the side pipe U¹, attached to the under side of the chest O³, and into the channel b², on the discharge side of bed plate at d¹, when it is led off to the boiler, or other receptacle designed to receive 95 or carry it off by the central, or end openings, 1¹ 1², as convenience or necessity may require.

From the above it will readily be seen that when the entrance valve to the cylinder B², 100 is open that to the cylinder B¹, is closed. While the discharge valve of the cylinder B² is closed, that of the cylinder B¹, is open, a change of motion of the plungers C¹ C², in the opposite direction requiring a reversal of their several positions from the above. 105

The passage of the fluid to and from the cylinders B¹ B² in both directions being understood, I will now explain the means whereby the valves of the main engine are 110 operated by the auxiliary engines, together with the means whereby it is operated and governed in its travel, thereby producing the reciprocating action of the plungers C¹ C² and limiting them in the amount of their 115 travel. The tappet or cross head D being

in contact with the jam nut g^1 (as shown) on the auxiliary engine valve motion rod f , by continuing its travel through the space h^6 , will during that time have just shifted 5 through the medium of the rod f , the valves $I^1 I^2$, over the ports $h^1 h^2 h^3 h^4$, thereby reversing their position from that shown, (the space h^6 I make equal to a little more than twice the breadth of the guide ports h^1 or 10 h^2), and having them come in contact with the stud e^1 , by its further travel through the space j^6 , (which I make equal to the breadth of the cut off valve ports j^1 or j^2), it will 15 through the medium of the motion rod H , have uncovered the ports $j^1 j^2$, admitting of free access of the entering fluid to act on the plungers $G^1 G^2$, by means of the brackets $V^1 V^2$, keyed to it, operating the valves $L^1 L^2$, in the chests $N^1 N^2$, through the agency of 20 the valve spindles $j^1 j^2$, while during this time, the advance of the rod H , moves the plunger pistons $G^1 G^2$, through the same space in the cylinders $F^1 F^2$, displacing the fluid in front of the plungers, which has full 25 liberty to escape through the ports $h^1 h^3$, and the exhaust openings $i^1 i^2$ and $h^1 h^2$, (the guide valves $I^1 I^2$, having fully shifted their position to allow of this early exhaust taking place prior to the commencement of the 30 uncovering of ports $j^1 j^2$), the cross heads $M^1 M^2$, during this time remaining stationary, they being loose on the rod H , but should the plunger pistons $G^1 G^2$, on the fluid gaining access to the cylinders $F^1 F^2$, 35 during the uncovering of the ports $j^1 j^2$, attain a greater speed than that with which the pistons $C^1 C^2$, and cross head D , is moving, the effect will be that of causing the stud e^1 , to move in advance of the cross head, and on 40 the stud e^1 , and bracket V^2 , reaching the cross heads $M^1 M^2$, to carry them along independent of any aid derived from the cross head D , but on the other hand, should the travel of the plungers $G^1 G^2$, be only equal 45 to, or less than that of the cross head D , then the duty of carrying forward the cross heads $M^1 M^2$, and the entrance and discharge valves governing the main cylinders $B^1 B^2$, devolves on the cross head D , until it has 50 carried them through the first half, or that portion of their travel which completes the covering of the ports to and from the cylinders $B^1 B^2$, when the plungers $C^1 C^2$, as also the cross head, cannot travel farther in 55 that direction. The uncovering of the opposite entrance and discharge ports to and from the cylinders $B^1 B^2$, is performed by the continued travel of the pistons $G^1 G^2$, until by the time they are fully uncovered 60 the ports $j^1 j^2$, will have just been covered by the valves $L^1 L^2$, the openings or space being so adjusted in them in connection with the required length of travel of the main valves, as to cause the entrance of the fluid 65 actuating the plungers $G^1 G^2$, to be shut off

from the cylinders $F^1 F^2$, at or slightly in advance of the main valves required travel in either direction. As a reserve or safety means of insuring against the injurious effect of their undue travel in either direction 70 in case of an accident to, or the breakage or removal of the cut off valves, or their attachment, I construct the plunger pistons $G^1 G^2$, in the manner represented, with openings or slots parallel to each other, at such 75 distance as taken in connection with the width of the shoulders or bridges $S^1 S^2$, running around their cylinders, as that with or without the cut off valves $I^1 I^2$, performing their duty, the travel of the plungers $G^1 G^2$, 80 will be limited to a given distance in each direction, as on the slots passing the bridges, the fluid gains access to both sides of the plungers, which bring them to a state of rest. The reversal of the main engine's 85 valves being effected, and the auxiliary engines at rest, on the return of the plungers $C^1 C^2$, with the cross head D , it comes in contact with and carries along the stud g^2 , the valve motion rod f , and the valves $I^1 I^2$, 90 until it reaches that part of its stroke, when all the parts are relatively in the same position on the left hand, as shown on the right hand in the drawings, when the same action takes place for the reversal of the valves 95 governing the direction of the plunger's (C¹ C²) stroke, as above described.

In connection with the machine, I employ a loaded valve Z^4 and air chamber Z^6 , between the source of supply and it, which admits of the escape of the fluid that cannot gain admittance to it, by the stop cock W being wholly or partially closed, while the air vessel takes off the jar or concussion incident to its use.

To record accurately the quantity of fluid passed through the machine from the cylinders $C^1 C^2$ by the reciprocating action of the plungers $B^1 B^2$, I register their travel in each direction as follows: A rod p , is keyed or otherwise firmly secured to the lower end of the cross head D . The ends working free in the barrels $s^1 s^2$, which serve the double purpose of guiding them in their travel to and fro in it, as also protecting the counter's action being tampered with. A cord r is wound around each of the barrels $s^1 s^2$ several times, and the ends made fast to the ends of the rod p , by which means motion is given to these barrels in accordance with the travel of the plungers $C^1 C^2$, the cross head D , the rod p , and the cord r . These barrels work free on their respective spindles $t^1 t^2$. On the side of each barrel a pin is attached on which a set of motion clicks, $u^1 u^2$, work (as their fulcrum) of which I employ four or five in a set. Their construction is such that commencing from the inside one, or that next the barrel, which call the shortest, they are from that to the outside 130

one which say is the longest, are each longer than the other by at least the distance due to their number divided into the space between the points of any two teeth on the wheels v^1 v^2 , and their ends are projected at an angle from their points, equal at least to the space of one division, so that when the point of one is at the bottom of the tooth nearest to it the angular part of the end at least covers the point of the next shortest click, by which arrangement, the end of one or more of the clicks is under all circumstances and in all positions in close contact against the teeth of the ratchet wheel they act upon, as the clicks have each a feathered elongation from their common center or fulcrum, which by means of another pin at the extremity nearly of their curved ends, springs each click into the tooth nearest to it. The ratchet wheels v^1 v^2 , are fast on their respective spindles t^1 t^2 , which gives motion to the usual train of wheel work within the counters Z^1 Z^2 thereby causing the hands or fingers on their faces to rotate in proportion to the motion given the counter barrels s^1 s^2 , by the travel of the plungers C^1 C^2 . A similar set of clicks Z^1 (Z^2 not shown) as described, acting as stops have their fulcrums, on the back of the counter cases, which play into the teeth of the stop ratchet wheels w^1 (w^2 not shown) which are likewise fast on their spindles t^1 t^2 .

When the barrel to the left is recording the travel of the plungers C^1 C^2 , in the direction of the arrows, or to the right, the barrel to the right is unrolling the cord wound around it and giving it to that on the left, which is taking it up in the same proportion and giving it out to the rod p , thereby always keeping it at a proper tension, and while the barrel s^1 is revolving in that direction carrying the ends of the clicks u^1 , over the face of the ratchet wheels teeth v^1 , the spindles t^1 is retained stationary by the back clicks Z^1 , on their ratchet wheel w^1 . The motion clicks u^2 , by the revolving of the barrel s^2 , carry around the ratchet wheel v^2 , and with it the spindle t^2 , thereby recording the plunger's travel in the arrow's direction. The stop ratchet wheel w^2 during the above action being carried around against the ends of the stop clicks s^2 , the same action taking place on the reverse travel.

I will now describe the construction and operation of the balanced sluice or gridiron valves which with but slight explanation will be readily understood by inspecting Figs. 6 and 7 of the drawings. The pressure on the upper side is practically balanced by recessing the under or face side between the ports, leaving a sufficiency only of metal to secure a proper bearing surface on the valve seat, as represented by the number 18 in Figs. 6¹ and 6². The valves so recessed

being adjusted with the ports in the seats whereon they work, in such manner, that when the ports in the seats are uncovered as shown at Fig 6², a slot or opening on the side of or through the seat, allows the passage of the fluid or other medium of pressure to act on the under or recessed part of the valve. And when the ports in the seat are covered, as shown at Fig. 6¹, that the under or recessed side of the valve shall still receive the medium of pressure, whereby the valve is partially balanced, whether at rest, in motion, at cover, or uncover of the ports, and if they were not so adjusted relatively to each other, communication would be made through the slots or openings at the side of the ports, or through the seat, between the upper and lower mediums of pressure.

In conclusion I would note the following minor details of construction and operation: 85 The entering fluid which operates the auxiliary engine's plunger pistons G^1 G^2 , has free passage to the valve chests N^1 N^2 , by the pipes o^1 , (o^2 not shown) from the entrance valve chests O^1 O^2 , and when displaced from 90 the cylinders F^1 F^2 , is led off from the central chests h^1 h^2 , into which it passes by the exhaust passage i^1 i^2 by pipes l^1 (l^2 not shown) which empty it in the central channel or well 1, in the bed plate 95 A, situated between the entrance and delivery channels b^1 b^2 , from whence it is carried off by a waste pipe. A small pipe is inserted in the cover of the chests N^1 N^2 , (not shown) their ends terminating in the 100 well of the bed plate, by which means whatever air may pass into the entrance valve chests with the fluid, will pass off by the pipes, o^1 o^2 into the chests N^1 N^2 , and from thence by those pipes, and previous to starting I perform the operation of blowing through, or expelling the air from the cylinders chests and passages &c., by opening the stop valves y^1 y^2 m^1 m^2 and x^1 x^2 , (some of which are not shown) when the air is 105 driven out and the fluid taken its place, they are to be closed.

I will now set forth wherein the advantages of the connection between the cross head on the main cylinder with the rods operating the valves of the main and secondary engines consists. The arrangement of the studs g^1 g^2 , on the rod f are at such distances thereon from each other, in connection with the arrangement of the studs e^1 e^2 , on the rod H , at such distance thereon from each other, in excess of that between g^1 and g^2 , as that during the travel of the cross head D, through the space h^6 , the auxiliary engine's guide valves (I^1 I^2) position 115 travel of the cross head D.

By making the cross heads M^1 M^2 , loose on the rod H , in connection with the attachment of the brackets V^1 V^2 , at such distance 120 from the studs e^1 e^2 , that the spaces j^6 j^7 , 125

which I make equal to or a little more than the breadth of the ports j^1 or j^2 , are contained between e^1 and e^2 , over and above that occupied by the cross heads M^1 M^2 , 5 therein, respectively. The effect produced by these devices in connection with those stated above are the following: The guide valves (I^1 I^2) governing the direction of the entrance and exhaust to and from the 10 auxiliary engines are in advance, efficiently and surely placed in position to perform their office, through the medium of the travel of the cross head D, in connection with the arrangement relative to each other 15 respectively of the studs g^1 e^1 , or g^2 e^2 , on their respective rods f and H, according to the direction of the plungers (C^1 C^2) travel, having accomplished which, during its further travel through the space j^6 or j^7 , in connection with the cross heads M^1 M^2 , being 20 loose on the rod H, the entrance ports j^1 j^2 , are fully uncovered by the time it completes that distance, thereby at this point placing the auxiliary engine's plunger pistons (G^1 25 G^2) in full and free communication with the medium of pressure that operates them, during which time, by the previous full reversal of the guide valves (I^1 I^2) position from that shown, the fluid displaced from 30 the cylinders (F^1 F^2) by the movement of the plunger pistons also through the space j^6 , has full and free liberty to exhaust through the port h^1 and the exhaust passage i^1 , from the cylinder F^1 , and the port 35 h^2 and the exhaust passage i^2 from the cylinder F^2 . The cross heads M^1 M^2 , during this time remain stationary. The rod H, working free through them, permits of the above stages of the machine's operation 40 being completed. Not only prior to the valves of the main engine (or cylinders C^1 C^2) governing the entrance and exit of the fluid to and from them being put in motion, but without imposing on the cross head D, the 45 additional duty, together with the jar or concussion incident to putting in motion the cross heads M^1 M^2 , and the main valves (which would be the case if the cross heads were attached to the rod H) except in case 50 of an accident by which the plunger pistons G^1 G^2 should fail to operate the valves of the main engine through the medium of the cross heads M^1 M^2 , by the time the stud e^1 passes through the space j^6 , and reaches the 55 position occupied by the cross head M^1 , and the bracket b^2 passes through the space j^7 , and comes in contact with the cross head M^2 . In that case, then the cross head D, comes 60 into operation as a reserve or safety means to close the valves of the main engine until it can travel no farther, by having taken up the cross heads during the continuance of its motion, and carried the main engine's valves over their ports, thereby closing the 65 entrance and exhaust to and from them,

when the plungers C^1 C^2 , and the cross head D, are brought to a state of rest. This provision effectually guards against the possibility of the plungers (C^1 C^2) undue travel, and endangering the safety of the machine 70 by bringing up on, if not carrying away the covers or ends of the cylinders in which they work, under such circumstances.

In proportioning the length of opening or slot in the valves I^1 I^2 relatively with 75 the desired length of travel of the main engine valves, as that taken in connection with their travel through the space j^1 or j^2 , which is distinct and independent from theirs. The ports j^1 j^2 , are covered by the valves I^1 80 I^2 , at or slightly in advance of the main engine's valves having fully reversed their previous positions whereby an undue travel of the auxiliary plunger pistons G^1 G^2 , the valve I^1 I^2 , and the main engine's valves 85 in either direction, is guarded against when the main engine's valve motion is derived from the auxiliary plunger pistons G^1 G^2 .

I do not claim operating the valves of the main engine or cylinders, by means of a 90 secondary or independent engine, the valves of which are actuated through the medium of the primary engine, the same being well known in the construction and operation of hydraulic engines, &c., but

What I do claim as my invention and desire to secure by Letters Patent is—

1. I claim operating in the manner and for the purpose herein described, the valves of secondary engine by the main engine 100 through a portion of their movement, and completing the same through the medium of the secondary engine.

2. I claim connecting the cross head of the main cylinder with its valves in the 105 manner described, so that said valves will close the ports of the main cylinder, in case the working parts of the secondary engine should fail to do their duty.

3. I do not claim the balancing of slide 110 valves, as such has heretofore been done in various ways, but what I do claim is forming a recess or recesses in the under or working side of the slide valve, in combination with the secondary opening or openings 115 through the seat, or in the side of the port or ports, for the purpose and in the manner, substantially as herein described.

4. I do not claim making a connection between opposite sides of the plunger piston 120 at a certain portion of its travel, as that has heretofore been done, but what I do claim is the combination of the bridge in the cylinder in combination with the openings in the plunger, for the purpose, and in the manner substantially as herein described.
